UNITED STATES PATENT OFFICE

153,332

DESIGN FOR A CHART HOUSING

Russell Howard Armstrong, Chicago, Ill., assignor
to Wayne Knitting Mills, Fort Wayne, Ind., a
corporation of Indiana

Application April 2, 1947, Serial No. 138,119

Term of patent 7 years

(Cl. D52—2)

To all whom it may concern:

Be it known that I, Russell Howard Armstrong, a citizen of the United States, residing in the city of Chicago, in the county of Cook and State of Illinois, have invented a new, original, and ornamental Design for a Chart Housing, of which the following is a specification, reference being had to the accompanying drawings, forming a part thereof.

In the drawing:

Figure 1 is a perspective view of a chart housing showing my new design.

Figure 2 is a cross sectional view taken substantially along the line 2—2 of Figure 1 looking in the direction of the arrows.

The side of the chart housing not shown is the same in appearance as the side shown and the opposite end is of plain surface.

I claim:

The ornamental design for a chart housing, as shown and described.

RUSSELL HOWARD ARMSTRONG.
